Attorney

UNITED STATES PATENT OFFICE.

FIELDING M. STARBUCK, OF SUMMERSVILLE, WEST VIRGINIA.

VAPORIZER FOR INTERNAL-COMBUSTION ENGINES.

Application filed April 13, 1923. Serial No. 631,952.

To all whom it may concern:

Be it known that I, FIELDING M. STARBUCK, a citizen of the United States, residing at Summersville, in the county of Nicholas 5 and State of West Virginia, have invented a new and useful Vaporizer for Internal-Combustion Engines, of which the following is a specification.

This invention relates to vaporizers for 10 use in connection with the intake manifold of an internal combustion engine.

The object of the invention is to provide 15 a device extending through the intake manifold and connected with the exhaust to provide a heated surface for contact with the fuel entering the manifold from the carburetor whereby the fuel is vaporized and rendered more readily combustible.

With the foregoing and other objects in 20 view which will appear as the description proceeds, the invention resides in the combination and arrangement of parts and in the details of construction hereinafter described and claimed, it being understood that 25 changes in the precise embodiment of the invention herein disclosed may be made within the scope of what is claimed without departing from the spirit of the invention.

In the accompanying drawings:—

30 Figure 1 represents a side elevation of a portion of an internal combustion engine showing the intake and exhaust manifolds with this improved attachment applied, and

35 Fig. 2 is a front elevation of the intake manifold showing it connected with the carburetor, parts being broken out and in section to disclose the attachment constituting this invention.

In the embodiment illustrated, an intake 40 manifold 1 is shown of usual construction except that the upright leg or pipe thereof is made open at its lower end and closed by a nut 2, the laterally extending tubular arm 3 being connected with the carburetor 5 as 45 shown at 4. Extending through the manifold 1 is a heating device in the form of a tubular member 10 which projects at its opposite ends through the manifold, the upper end 11 thereof being threaded for connection with a flexible pipe 12 which unites 50 it with the exhaust manifold 13 by a coupling 14 so that the heated gases from the exhaust will be fed through pipe 12 into pipe 10 and pass out through its open lower

end to the atmosphere. This tube 10 is here 55 shown equipped with a fuel absorbing medium in the form of an asbestos fiber tubular wick 15 which will absorb the fuel admitted from the carburetor, permitting saturation of the wick by capillary attraction. Around 60 this wick 15 is arranged a resistance or heating coil 16 disposed exteriorly of the tube 15 and having one terminal 17 connected to and insulated from the manifold while the other terminal 18 is connected to the tube 65 10. This wick 15 and resistance coil 16 are similar to those shown in my Patent No. 1,194,437, dated August 15, 1916, and are designed to heat the fuel and vaporize it to facilitate starting of the engine. 70

It will thus be seen that the tube 10 which is arranged longitudinally in the path of the fuel passing from the carburetor to the cylinder will present a heating surface and the entering fuel and cause it to vaporize 75 and pass into the cylinder in a readily combustible condition, the heat being supplied to said tube 10 after the engine is started from the exhaust manifold in the manner above set forth the electric heating coil 80 80 which initially heats the fuel to facilitate starting being cut-off by any suitable means, not shown.

Various changes in the form, shape, proportion and other minor details of construction may be made without departing from 85 the principle or sacrificing any of the advantages of the claimed invention.

I claim:—

The combination of an intake manifold 90 of an explosive engine, a pipe extending through said manifold and adapted to be connected to the exhaust of the engine, a fibrous fuel absorbing tube surrounding said pipe within the manifold, an electric resist- 95 ance coil surrounding said tube and connected to initially heat the fuel absorbed by the tube to facilitate starting of the engine the pipe connected with the exhaust continuing the vaporizing of the fuel after 100 the electric heater has been cut-off.

In testimony that I claim the foregoing as my own, I have hereto affixed my signature in the presence of two witnesses.

FIELDING H. STARBUCK.
